UNITED STATES PATENT OFFICE.

ROY M. MOSS AND OSCAR B. PULIS, OF MILWAUKEE, WISCONSIN, ASSIGNEES TO METAL FORMS CORPORATION, OF MILWAUKEE, WISCONSIN, A CORPORATION.

WALL FORM.

Application filed July 3, 1924. Serial No. 724,138.

To all whom it may concern:

Be it known that we, Roy M. Moss and OSCAR B. PULIS, citizens of the United States, residing at Milwaukee, in the county 5 of Milwaukee and State of Wisconsin, have invented certain new and useful Improvements in Wall Forms, of which the following is a specification.

This invention has to do with what are 10 known commonly as metal wall forms, and involves construction features useful preferably for straight all form units, though certain essential features are equally adapted for use on circular wall or mold forms of 15 the metal type.

It is customary to hold metal wall forms in position, properly spaced apart, by means of tie wires which are embedded in the concrete wall built by the use of the forms.

20 An object of our invention has been to do away with the need of employing the tie wires, the use of which involves a rather expensive operation of twisting or adjusting in connection with the forms. We have devised 25 a special connection for holding the forms in spaced relation, said connection being used in conjunction with movable locking or wedging devices carried by the form units.

30 Our invention furthermore involves a novel type of metal form unit clamp for connecting units together.

Our invention additionally involves a 35 special cooperative construction of tie rod connector between spaced units, locking means therefor, and clamping means for connecting sections or units, together with other detailed features of construction that will appear more fully as this description 40 proceeds.

In the accompanying drawings:

Figure 1 is a sectional view showing tie 45 rod members arranged to connect spaced form units or sections and locked in place by means of the invention.

Figure 2 is a sectional view showing how the spaced form units are spaced apart and aligned by horizontal aligners and bringing out more clearly the cooperation of the 50 tie rods, locking wedges or members, and clamping members.

Figure 3 is a sectional view taken about on the line 3-3 of Figure 1.

Figure 4 is a front elevational view 55 bringing out more clearly certain arrange-

ments and constructions illustrated in the other figures of the drawing.

Figure 5 is an enlarged detail view bringing out the coaction between the locking member or wedge and the clamp. 60

Figure 6 is a sectional view taken about on the line 6-6 of Figure 5.

We have illustrated in our drawings metal forms of a type known on the market today as "metaforms". These forms consist of 65 metal plates 1 equipped at their edges with angle plates or bars 2 and assembled by being placed together edge to edge, so to speak, or angle bar edges flat against one another. The angle bars 2 form flanges 4 70 at the edges of each of the wall form units or sections which are as a whole designated as A. If desired, the plates 1 of each form unit may be reinforced by intermediate angle bars or plates 3. This latter is im- 75 material to the invention.

Referring to Figure 2 it will be observed that two sections or units of "metaforms" are set up in vertical positions spaced apart. A number of these sections in horizontal 80 arrangement will be held aligned by horizontal aligners B having suitable means C to connect them with the forms or units, these features not having to do particularly with our present invention. 85

To connect the spaced forms or units A together in substitution for the tie wires ordinarily employed, we utilize tie rods 5. These rods pass through openings at the edge portions of the forms and through 90 openings in the angle plates 2 located at such portions.

As it is desirable to positively prevent separating movement of the forms A when properly spaced we provide in the flanges 4 95 of adjacent units vertical or other slots through which pass the locking members in the form of wedges 6. The wedges 6 are adapted to engage either one of two tie rods 5 that pass transversely through the form 100 units, and thus lock the latter positively in proper relative positions. For facilitating the operation of one wedge 6 with two adjacent parallel tie rods 5 as seen in Figure 1, the tie rods may be arranged to pass through openings in slightly different horizontal planes, so that the wedging edge of the member 6 may have effective coaction 105 with the two rods.

We have designed a special form of clamp 110

for our forms. This clamp is seen best in Figures 5 and 6 and is designed to engage adjacent abutting flanges of two adjacent forms, as seen in Figure 4, to lock the forms together. Clamps like those of our invention as heretofore used have been riveted to the flanges 4 of the forms and supported wholly by said flanges. The tendency of a clamp so fastened is at times to pull the rivet 10 through the angle plate 2 if any unusual strain is placed upon the said part.

To avoid the foregoing objection we have applied to the form section a casting or bracket 7 to form a bearing or support for 15 the rivet 8 which pivotally connects one jaw 9 of the clamp 10 to the angle plate 2. By using the bracket 7 which is itself riveted to the form unit on top of the angle plate 2, we obtain a bearing for the rivet 8 at 20 both of its ends, and this strengthens the connection of the rivet to the form or unit in a very satisfactory way in practice. The jaw 11 of the clamp 10 is spaced from the jaw 9 and the manner in which the two 25 jaws engage the flanges 4 of the forms or units is quite evident on reference to Figure 6. We note, however, that the jaw 9 is formed with a downwardly extending projection 9^a that is apertured for the reception 30 of the rivet 8 by which the clamp is pivoted upon the parts by which it is supported.

In conjunction with the tie rod feature of our invention we find it useful to create 35 an interlock between the clamp 10 and the wedge or locking member 6 and this is done by so arranging the said parts that the locking member when engaged with one or more of the rods 5 is adapted to correspondingly engage the upper portions of 40 the jaws 9 and 11 of the clamp 10, as seen in Figure 5. Thus accidental disengagement of the clamp 10 from the angle plate flanges 4 is absolutely prevented, and if desired the clamp 10 may have slight shoulders 11' and 9' on the jaws 11 and 9 respectively to positively abut with a side of the locking member 6 when the parts 6 and 10 are in cooperation.

50 It will, of course, be evident that the shoulders 9' and 11' are not needed for the purposes of the invention. We comment also upon the fact that to subserve the rigidity of the connection between the various parts as described we preferably employ a bracket 12 somewhat like the bracket 7, on the edges of the form units which fit against the edges which carry one or more plates 7. The two brackets 7 and 12 afford 55 very ample bearing for the wedges or locking members 6 that coat with the tie rods 5, a considerable greater bearing than afforded solely by the slots in the flanges 4 through which the wedges 6 pass.

65 The employment by us of the rods 5 fa-

cilitates greatly the setting up of our form units in getting ready for work as much time is saved over the practice of using the tie wire connections. Also the units may be more accurately positioned respecting one another than is obtainable by the old method. In practice we have found our whole system of tie rod connections and clamp or locking member cooperation, extremely effective in use to provide a rigid 70 setting up of the metal forms, and obviate possibility of displacement or breaking off of the clamping means intermediate the units.

Having thus described our invention what 80 we claim as new and desire to secure by Letters Patent, is:

1. In combination, spaced form units, tie rods extending across the space between the units and having their opposite ends passing 85 through the latter, angle plates on the form units adjacent to the ends of the rods, and wedges slideable at right angles to the tie rods and engageable with the latter to lock them connected with the form units, and clamps connecting the form units together and cooperating with said wedges.

2. In combination, a form unit comprising a plate having an edge flange, a jaw clamp pivoted to said plate and having its jaws adapted to embrace the edge flanges of two adjacent units for clamping the same together, a tie rod passing through the form unit at substantially right angles thereto, and a locking member intermediate said rod 100 and the clamp and movable to engage the rod to lock the same in relation to the unit.

3. In combination, spaced form units, a tie rod extending transversely therethrough and across the space therebetween, and locking members for holding the tie rod positively against movement relatively to the form units, and separate clamps for securing the form units together adapted to be engaged by the locking members of the tie 105 rods and prevented from movement by such cooperation.

4. In combination, spaced form units, tie rods extending across the space between the units and having their opposite ends passing 115 through the latter, angle plates on the form units adjacent to the ends of the rods, and wedges slideable through said angle plates at right angles to the tie rods and engageable with the latter to lock them connected with the form units, and clamps connecting the form units together and cooperating with said wedges, and said clamping members comprising jaws to embrace and clamp together the angle plates attached to the form units, thus clamping the form units in operative connection.

5. In combination, a form unit provided with an edge flange, a bracket applied to said flange and spaced therefrom, a clamp 130

- pivoted to said form unit and having flange embracing jaws, and a pivot connecting the clamp to the form unit and supported by said flange and said bracket.
- 5 6. In combination, a form unit provided with an edge flange, a bracket applied to said unit and spaced from the flange, a clamp pivoted to said form unit and having flange embracing jaws, and a lever for connecting one of the jaws of the clamp to the form unit and mounted with its ends supported by the angle plate and said bracket, substantially as set forth.
- 10 7. In combination, a form unit comprising a plate having an edge flange, a jaw clamp pivoted to said plate and having jaws to embrace the edge flanges of adjacent plates whereby to connect the plates together, and
- 15 a locking member to engage said clamp and interlocked with the unit so as to prevent unauthorized movement of the clamp.
8. In combination, a form unit comprising a plate having an edge flange, a jaw clamp pivoted to said plate and having jaws to embrace the edge flanges of adjacent plates whereby to connect the plates together, and a locking member to engage said clamp and mounted so as to prevent unauthorized movement of the clamp, and a tie rod passing through the plate of the form unit and adapted to be engaged by said locking member.

In testimony whereof we affix our signatures.

OSCAR B. PULIS.
ROY M. MOSS.
